ADJUSTABLE ELECTRIC FAN

Arthur K. Tateishi, Toronto, Ontario, Canada

Application June 9, 1954, Serial No. 30,874

Term of patent 14 years

(Cl. D26—7)

FIG. 1

FIG. 2

FIG. 3

To all whom it may concern:

Be it known that I, Arthur K. Tateishi, a citizen of the Dominion of Canada, and a resident of Toronto, Ontario, Canada, have invented a new, original, and ornamental Design for an Adjustable Electric Fan, of which the following is a specification, reference being had to the accompanying drawing, forming a part hereof.

In the drawing:

Fig. 1 is a front perspective view of an adjustable electric fan, showing my new design.

Fig. 2 is a side view of Fig. 1, and

Fig. 3 is a rear perspective view of Fig. 1 on a reduced scale.

I claim:

The ornamental design for an adjustable electric fan, as shown.
